G. C. TROTTER

PHONOGRAPH

Filed Nov. 27, 1922

UNITED STATES PATENT OFFICE.

GEORGE C. TROTTER, OF ELKHART LAKE, WISCONSIN, ASSIGNOR TO LAKE LABORATORIES COMPANY, OF ELKHART LAKE, WISCONSIN, A CORPORATION OF WISCONSIN.

PHONOGRAPH.

Application filed November 27, 1922. Serial No. 608,407.

To all whom it may concern:

Be it known that I, GEORGE C. TROTTER, a citizen of the United States, residing at Elkhart Lake, in the county of Sheboygan and State of Wisconsin, have invented certain new and useful Improvements in Phonographs, of which the following is a specification.

This invention relates to a phonograph of the type which employs a turntable on which is mounted the usual grooved record, and more particularly it has to do with such a phonograph which is electrically operated, and with a novel switch by which its operation is controlled, it being an important object of my invention to devise for this purpose a switch of special construction.

In the accompanying drawing is shown an exemplification of this invention in the manner following:

Figure 1 is a fragmentary plan view of a conventional phonograph equipped with the present switch;

Fig. 2 is a side elevation of the operating parts of the phonograph, a portion of the motor board and turntable being exhibited in section in the plane of line 2—2 of Fig. 1;

Fig. 3 is a detail in longitudinal section of the turntable spindle per se;

Fig. 4 is a view in plan of the spindle cap which serves as a switch; and

Fig. 5 is a vertical section therethrough.

The parts of the talking machine which are illustrated in the drawing, and which may follow usual constructions, include an electric motor A which is carried upon a base B that is secured to the under side of the motor board C; suitable driving connections extend from the motor to a specially constructed spindle D which is journaled in the base, the spindle being projected in the base, the spindle being projected therethrough and through the motor board to provide on its upper end a mounting for the turntable E on which is rested a disc record F; and connected with a suitable sound chamber (not shown) is the usual tone arm G, equipped with a reproducer H and adapted to swing inwardly across the record as its needle is tracked in the grooves thereof. It is with a phonograph answering to this general description that the improvements forming my invention are especially adapted for use.

Referring now to Fig. 3 in particular, I

have shown a spindle provided with a central aperture in the form of a bore 10 extending downwardly from its top through a substantial portion of its length, the bore at its lower end communicating with a lateral bore 11 which opens upon one side of the spindle. Above this lateral bore is an insulating collar 12 adapted to fit rotatably within an opening 13 which extends through the motor base; and extending from the lower spindle end is a trunnion or pin 14 which is journaled in a bearing 15 that depends from the motor base, the spindle being thus supported and steadied at these two points to ensure its rotation about a fixed vertical axis.

A conductor sleeve or band 16 surrounds the collar 12 in its lower region, and in spaced relation to the motor base, and fastened thereto is one end of a suitably insulated conductor 17 in the form of a wire which extends through the two bores 11 and 10 to connect at its opposite end with a stud or pin 18 having a head 19, all as shown clearly in Fig. 3. In the upper end of the spindle bore 10 which is slightly enlarged, is secured an insulating bushing 20 formed with a seat to receive the stud head, the bushing thus providing a mounting in which the stud is fixedly held in insulated relation to the surrounding parts. By this construction also, the stud head presents its upper face substantially flush with the proximate end of the spindle whereon are formed certain external threads 21 which proceed downwardly from an annular shoulder 22 just below the spindle end.

As shown, the turntable E is formed for mounting on the spindle so as to rotate therewith, the spindle projecting therethrough and through the record F in the usual manner. Arranged to co-operate with the spindle is a cap I formed with a body 23 from which depend circular walls 24; and extending laterally from the cap base are a pair of arms 25 and 26, diverging approximately at an angle of about 90°. The former of these arms, which is short, has a pointed extremity 27, while the other arm 26 is extensible with the aid of a slide piece 28 the edges 29 whereof are bent to overlie the arm 26 for frictional connection therewith. From this arm is extended upwardly a tongue 30 adapted to engage the overlying edges 29 when the slide piece is extended.

outwardly to a desired distance. The outer end of the slide piece terminates in the form of an eye 31 of substantially the same internal diameter as the internal diameter

5 of the walls 24, the purpose being to adapt the eye also for fitting over the spindle end, when occasion requires. Extending laterally from the side of the eye which is remote from the cap is an abrupt shoulder 32, 10 the purpose of which will shortly appear.

The exterior of the cap may be of any suitable configuration, but preferably is milled or serrated as at 33 to facilitate handling. In its circular walls I have provided a longitudinal slot 34 in which is received a spring 35, preferably of wire, having its upper end 36 secured to the cap in any approved manner. At its lower end the spring is inwardly crimped to provide a 15 rounded head 37 which normally projects into the chamber within the lower cap end. With such a construction the spring yieldingly opposes a placing of the cap over the spindle end, the spring head being forced 20 back in the shoulder 22 before it may reach a lower position where it may engage with the spindle threads 21. When so positioned, however, the spring head may either ride in such threads, if a relative rotation ensues, or slide crosswise of them, provided 25 that a sufficient vertical force be applied.

In the cap body is a central aperture which extends through from its top to the chamber at the lower end. As shown, 30 this aperture is of smallest diameter at the bottom, where it accommodates a pin 38 having a head 39 adapted to rest upon the seat formed by an abrupt increase in the diameter of the aperture; and bearing down upon the pin head is a 35 compression spring 40 which is confined in place as by means of a screw 41 that is threaded into the aperture from the top of the cap. By some such means as this, I provide in the cap chamber a pin which is 40 adapted to engage yieldingly the head of the stud 18 when the cap is pushed down sufficiently over the spindle end; the pin head, however, limits the outward movement 45 of this part so as to avoid contact with the stud except when the cap is pressed down over the spindle a sufficient distance for this purpose.

The electrical circuit connections used with 50 the present construction may be very simple. As a suggestive layout, I have shown one lead X running to an insulation block 42 which is mounted on the motor base, this lead connecting with a suitable brush 55 43 which bears constantly against the circular band or sleeve 16. The circuit is then taken through the wire 17 to the stud 18, and through the cap, when this part is fitted 60 down in place, to the spindle which is 65 grounded; a grounded connection in the wire

Y also extends from one pole of the motor, as shown. The other lead Z is connected with the opposite pole of the motor in the usual manner.

In the use of a phonograph which embodies the features of my invention, the operations are about as follows: A record disk is arranged upon the turntable, following which the extensible arm of the cap is properly adjusted. It is contemplated that this should be set to stop the motor when the record ceases to play. Accordingly it will be found convenient to fit the eye of the extension arm over the spindle end and then adjust the arm with the pointer 27 lying about even with the innermost playing groove of the record. Having set the parts accordingly, the reproducer is placed in the proper position for playing, and the cap fitted over the spindle end. To start the motor the cap is pressed down to establish contact between the pin 38 and stud 18. A circuit is now completed and the motor is set in operation, the cap being rotated with the spindle.

When the reproducer needle 45 has tracked through the record grooves to an innermost position, it will lie in the circular path of the extension arm; at this point the needle engages the shoulder 32 to arrest further rotation of the cap. With continued movement of the spindle, however, the spring head 37 is tracked in the spindle threads 21, thus effecting a raise in the position of the cap until the pin 38 breaks contact with the 100 stud 18. The electrical circuit is thereupon broken so as to stop the motor. It will be apparent, therefore, that this invention controls both the starting and stopping of the motor, at any selected point in the playing 105 of the record.

It is clear that the present improvements may be embodied in a number of different forms only one of which has herein been suggested. Except as the appended claims 110 may contain express limitations, it is not to be inferred that the principle of my invention is restricted in its application to the exemplified structure shown, as manifestly it is possible to use other forms, and in other adaptations, which would fall equally within the spirit and scope of my invention.

I claim:

1. In a phonograph, the combination of a 120 turntable, a rotatable spindle on which the turntable is mounted, an electric motor drivingly connected with the spindle, circuit connections leading from the motor to a point adjacent the upper end of the spindle, and means providing a switch at the upper spindle end, substantially as described.

2. In a phonograph, the combination with an electric motor, a spindle adapted to be rotated thereby, a turntable associated with 130

the spindle adapted to receive thereon a grooved record, and a reproducer needle adapted to track in the record grooves and move toward the spindle, of circuit connections leading from the motor to a point adjacent the upper end of the spindle, and means arranged at the spindle upper end adapted to make or break said circuit whereby operation of the motor is controlled, said 10 means being actuated to break the circuit by movement of the reproducer needle, substantially as described.

3. The combination with a phonograph having an electric motor, a spindle drivingly connected therewith, and a turntable associated with the spindle, of circuit connections leading from the motor through the spindle to a point adjacent its upper end, said connections including a cap movably fitted to the spindle end, there being a spring pressed element mounted in the cap adapted when the latter is in one position to close the circuit and when in another position to break the circuit, substantially as described.

25 4. The combination with a phonograph having an electric motor, a spindle drivingly connected therewith, a turntable associated with the spindle and adapted to support a grooved record, and a reproducer equipped with a needle which tracks in the grooves of the record to move toward the center thereof, of circuit connections extending from the motor through the spindle, said connections including a cap movably fitted to the spindle and adapted when in one position to close the circuit and when in another position to open the circuit whereby the operation of the motor is controlled, and means associated with the cap adapted for engagement by the 35 reproducer needle to effect a change in the position of the cap to thereby open the circuit, substantially as described.

5. In a phonograph, the combination with an electric motor, a turntable drivingly connected therewith adapted to receive thereon a grooved record, and a reproducer having a needle adapted to track in the record grooves and move toward the center thereof, of circuit connections extending from the 45 motor through the turntable to a point above the record, said connections including also a switch detachably arranged above the record whereby the circuit may be opened or

closed to control the operation of the motor, substantially as described.

6. In a phonograph, the combination with an electric motor, a turntable drivingly connected therewith and adapted to receive thereon a grooved record, and a reproducer having a needle adapted to track in the record grooves and move toward the center thereof, of circuit connections extending from the motor to a point above the turntable and including a switch for opening and closing the circuit, and means associated with the switch adapted for engagement with the needle when moved to a predetermined point to thereby open the switch, substantially as described.

7. In a phonograph, the combination with an electric motor, a turntable, and a spindle drivingly connected therewith, of circuit connections leading from the motor through the spindle to a point adjacent its upper end, and a cap removably fitted to the spindle forming part of said connections, the spindle being formed with threads and the cap having means yieldingly engaging therewith, whereby the cap may be screwed upon the threads or be moved thereacross, the cap when in one position longitudinally of the spindle being adapted to close the circuit, and when in another position to open the circuit, substantially as described.

8. In a phonograph, the combination of a spindle having a central aperture extending to the upper end thereof and communicating at its lower end with a lateral passage, a stud secured within an insulated mounting at the upper spindle end, a sleeve having an insulated mounting at another place upon the spindle, an insulated wire connecting the stud and sleeve, means adapted to be fitted onto the upper spindle and to establish an electrical circuit between the stud and spindle body, the latter being grounded, means adapted for rotation by the spindle to reproduce sound, an electric motor drivingly connected with the spindle, and connections from a source of current to the motor, one pole of which is grounded and the other connected to the insulated sleeve to establish a complete circuit, substantially as described.

GEORGE C. TROTTER.
